(57) **CLAIM**

I claim the ornamental design for a pencil and crayon sharpener, as shown and described.

DESCRIPTION

FIG. 1 is a perspective view of the pencil and crayon sharpener of the claimed design.

FIG. 2 is a view of the front end of FIG. 1;

FIG. 3 is a right side view of FIG. 1, the opposite side being a mirror image of the right side;

FIG. 4 is a rear end view of FIG. 1; and,

FIG. 5 is a perspective view of the end opposite from FIG. 1. The broken lines are included for the purpose of showing features that form no part of the claimed design.

1 Claim, 4 Drawing Sheets
